DELAY COMPOSITIONS

Hugh M. Kerr, Cartierville, Quebec, and Gordon Towell, Brownsburg, Quebec, Canada, assignors to Canadian Industries Limited, Montreal, Quebec, Canada, a corporation of Canada

Application March 29, 1956, Serial No. 574,663

Claims priority, application Canada August 3, 1955

4 Claims. (Cl. 52—2)

This invention relates to substantially gasless, slow burning delay compositions for use in delay fuses of various types and more particularly for use in the delay fuses for ventless delay electric blasting caps.

The prior art delay compositions are either of the gas-generating or gasless class. Those of the gas-generating class evolve a large volume of gas when burning and burn at a relatively slow rate, while those of the gasless class burn with the evolution of little or no gas and usually at a relatively fast rate.

The most common commercial use for delay compositions is in the delay fuses or elements of delay electric blasting caps. Delay electric blasting caps generally comprise, as essential components, an electrical ignition means, an ignition charge, a detonating charge and a delay element interposed between the ignition and detonating charges through the medium of which the detonating charge is fired after a predetermined delay interval. The delay element is customarily a fuse of such length and composition as will afford the desired delay interval between firing of the ignition and detonating charges.

Delay electric blasting caps which are commercially available are generally of three types: the short interval ventless delay type which uses relatively fast burning gasless delay compositions and which has delay intervals ranging from a few milliseconds to approximately one second; the vented slow delay type which commonly uses gas-generating delay compositions such as black powder and which has delay intervals ranging from about $\frac{1}{2}$ second to 15 seconds and longer; and the ventless slow delay type which commonly uses gasless delay compositions and which has delay intervals of the same order as the vented slow delay type.

In the vented slow delay type of electric blasting cap, the gas-generating delay composition produces a large volume of gas when burning. Therefore, the cap casing is vented to permit the free escape of the gases which, if not released, would cause an increase in the burning rate of the delay composition because of the pressure generated, and hence would produce irregularities in the delay interval of the cap. In the extreme case the pressure build-up might result in the delay composition exploding, thus causing an almost instantaneous detonation of the main explosive charge.

Vented caps have a number of serious disadvantages. Although the vent in the cap is usually sealed with a rupturable membrane to prevent the entrance of moisture, these caps have been found to be much more susceptible to water penetration than comparable caps with a solid casing. Furthermore, flashes from the burning delay composition may escape through the vent and may cause premature burning of the primed explosive charge. There is also a serious history of this type of cap misfiring in wet ground where the shock from charges fired by vented delay caps of relatively short delay intervals forces water through the vents of neighbouring vented delay caps of relatively longer delay intervals, thus wetting and quenching their burning delay trains. Should

2

the vent hole inadvertently be blocked up or improperly aligned, a pressure build-up may also occur within the casing when the delay composition is ignited, with a resultant irregular burning of the fuse and, hence, an irregular delay interval.

Both the slow delay and short interval delay ventless caps need not be vented since they use gasless delay compositions. Thus, they avoid the disadvantages of the vented delay caps. However, despite their useful properties, the gasless delay compositions of the prior art suffer from serious practical disadvantages when used in delay electric blasting caps with delay intervals of the order of the vented slow delay caps. These prior art compositions either burn at a rate such that the length of delay element required to produce the long delay intervals desired necessitates a cap casing which is inconveniently long for priming explosive cartridges, or they are so sensitive to moisture that extreme care must be taken to exclude moisture from the cap and its component parts and compositions.

Gasless delay compositions generally comprise a mixture of oxidising and fuel materials. The materials are selected and proportioned such that, upon ignition, the decomposition products of the oxidising materials are solids and gases, which gases react with the fuel material to form other solid products. Thus, all products of combustion are solids and essentially no residual gases are produced. The materials must also be so selected and proportioned that the burning temperature of the composition after ignition is sufficiently high to generate the heat required to sustain combustion throughout the length of the delay element and to subsequently initiate the explosive charge.

The burning speed of the prior art gasless delay compositions may be reduced by the judicious selection and proportioning of the ingredients and by the addition of inert materials which retard oxidation and, hence, slow down combustion. Attempts have been made to produce slow-burning, gasless delay compositions by these and other means but all such compositions produced have had one or more serious disadvantages. Some are difficult to ignite and some generate insufficient heat to sustain combustion throughout the length of the delay element, thus causing misfires in the delay caps in which they are used. Others are chemically unstable and deteriorate, particularly when the caps in which they are used are subjected to heat and/or humidity during storage or use. Still others burn erratically with the result that the delay for a given length of element cannot be predicted and the delay intervals obtained for caps with elements of the same length vary widely.

It is an object of this invention to provide a gasless delay composition which will burn at a relatively slow, even rate with the generation of sufficient heat to sustain combustion throughout the length of a delay element and to substantially initiate the explosive charge, and which is also readily ignited. A further object is to provide such a gasless delay composition which is chemically stable and which is not markedly affected by changes in moisture content such as would be expected in a cap assembly. A still further object of the invention is to provide a gasless delay composition burning at a slow, even rate which makes possible the fabrication of a precise and accurately timed series of ventless delay caps having delay intervals of large fractions of a second and longer and in cap shells substantially shorter than most other known slow ventless caps.

The essentially gasless, slow-burning delay composition of this invention comprises, as essential ingredients, silicon, solid non-metallic material selected from the group consisting of selenium and tellurium, and oxidising

material selected from the group consisting of lead oxides and water-insoluble metallic chromates.

The preferred oxidising agents for use in the composition of the invention are lead peroxide, red lead, barium chromate and lead chromate.

It is possible to formulate a series of delay compositions of the aforesaid type with varying burning rates by the judicious proportioning of the ingredients. However, since a main object of the invention is the provision of a slow-burning delay composition which will make possible the fabrication of a precise and accurately-timed series of ventless delay caps having delay intervals of large fractions of a second and longer and in cap shells substantially shorter than most of those of comparable delay heretofore known, it is preferable to limit the proportion of silicon in the delay compositions generally and also the ratio of silicon to selenium and/or tellurium in the fuel. It is thus preferable generally to use not more than 65% of silicon, by weight of the delay composition and when the oxidising material is comprised solely of chromates, not more than 40% of silicon by weight of the delay composition. For the same reason, it is preferable to have at least a minimum proportion of silicon in the fuels of the delay compositions, as shown in the table of preferred compositions below, in which all parts and percentages are by weight and the fuel ingredients are silicon, selenium and/or tellurium.

TABLE

	Delay Composition		
	A	B	C
Oxidising Material Ingredients.	Lead Oxides and/or Chromates.	Pb ₃ O ₄ and/or PbO ₂ .	BaCrO ₄ and/or PbCrO ₄ .
Parts Delay Composition.	100.....	100.....	100.....
Parts Fuel.	6.5-50.....	7-65.....	10-40.....
Parts Oxidising Material.	93.5-50.....	93-35.....	90-60.....
Min. Percent Silicon in Fuel.	60.....	17.....	80.....
Percent Lead Oxides in Oxidising Material.	30-100.....	100.....	0.0.....

The compositions of the invention also include all compositions which may be produced by combining compositions "B" and "C" shown in the above table in all proportions.

The gasless delay compositions of the invention are readily prepared by means well known to the art. It is preferable to use particularly finely ground fuels and oxidising material in the compositions, the particle sizes of which are much smaller than the largest particles which will pass through a 250-mesh Tyler screen. After grinding and screen, if necessary, the ingredients are thoroughly mixed by well known methods.

The application of the invention in ventless delay electric blasting caps may be more readily understood by reference to Figure 1 in the accompanying drawings which shows a longitudinal sectional view of a preferred form of ventless delay electric blasting cap.

Figure 1 shows a ventless delay electric blasting cap in which 1 is a solid drawn cylindrical metal shell in the base of which is pressed a suitable detonating charge 2 such as, for example, tetryl or pentaerythritol tetranitrate. Directly above the detonating charge is pressed a suitable priming charge 3 on top of which is pressed a delay element 4 containing the gasless delay composition 5. The priming charge 3 may be, for example, a mixture of lead azide and lead styphnate or the like, while the delay element comprises a lead tube containing the gasless delay composition 5 which is seated at such a pressure that a gastight seal is made with the shell wall 1. The bridge wire 6 is soldered or welded to the terminals of the two leg wires 7 and 8. A rubber plug 9 carries and sup-

ports the two leg wires 7 and 8 and seals off the open end of the cap shell 1. An essentially gasless loose charge ignition composition 10 such as, for example, a corned mixture of 98% by weight of red lead and 2% by weight of boron, surrounds the bridge wire 6 and substantially fills the space between the rubber plug 9 and the delay element 4.

The delay fuse may be prepared by tamping the delay composition into a large diameter lead tube closed at one end which, when full, is closed at the open end and sized down by rolling, drawing or rotary swaging to any desired diameter. It is preferable to select a lead tube of such external and internal diameters that when it is subsequently sized down into a delay fuse with an external diameter of about 0.25 inch it will contain a delay composition train about 0.125 inch in diameter. The delay elements are prepared by cutting the delay fuse into segments of such length that when used in delay caps, the desired delay intervals are obtained.

Example 1

Two preferred compositions illustrative of the invention were prepared having the following compositions:

25	Ingredients	Composition 1 (percent by weight)	Composition 2 (percent by weight)
30	Selenium.....	1.6	1.7
	Silicon.....	6.2	6.1
	Red Lead.....	36.0	36.0
	Lead Chromate.....	35.9	35.9
	Barium Chromate.....	20.3	20.3

These compositions were prepared and compressed into delay elements by methods described above and were used in the heretofore described ventless delay electric blasting caps. The following table illustrates a series of these caps wherein the delay elements were of different lengths.

TABLE

45	Composition	Element Length in inches	Mean Delay Interval, Secs.	No. of Caps Tested
1.....	0.30	1.76	19	
1.....	0.90	5.76	15	
1.....	1.50	9.80	16	
2.....	0.30	1.85	23	
2.....	0.90	6.06	24	
2.....	1.50	10.22	23	

The experimental data are graphically illustrated in Figure 2 of the accompanying drawings. Figure 2 is a graphical plot of the mean delay intervals obtained in the tests illustrated in the above table against the length of delay element used in the caps. The solid lines represent the curves obtained from the tests while the dotted lines are extrapolations of these curves.

The straight-line relationship which exists between the element length and mean delay interval when delay compositions of the invention are used is clearly illustrated by Figure 2. It has been found that the curve based on experimental data can be extrapolated and used to predict the delay intervals of caps using elements of greater length than those for which data are available. For example, using the graph of Figure 2, it can be predicted with a reasonable degree of accuracy that a ventless delay electric blasting cap, as heretofore described, having a mean delay interval of, say 16 seconds, can be obtained by using approximately a 2.4 inch length of delay element containing the above-described composition 1.

One of the main disadvantages of most of the prior art gasless delay compositions is that their burning rates are too high for efficient use in slow delay electric blasting

caps. When used in delay elements of ventless delay electric blasting caps such as heretofore described, they result in inordinately long caps when delay intervals of large fractions of a second and longer are desired. For example, most commercially available slow delay gasless electric blasting caps range in length up to 5 inches or greater. Caps of this length are undesirable because when used to prime standard explosive cartridges of say 8 inches in length, they must penetrate very nearly the whole length of the cartridge. If the explosive material in the cartridge is stiff due to material characteristics or weather conditions, this becomes a difficult and time-consuming operation. Also, if extreme care is not taken, the cap may be inserted at a slight angle which might result in it protruding through the side of the cartridge. Thus, when loading a borehole, there would be a danger of premature detonation due to a protruding cap striking the side of the borehole or of an unexploded charge if the cap fires properly but dissipates its power outside the charge.

To obviate these difficulties those skilled in the blasting art prefer to use caps of a maximum length of about 4 inches. Using the delay compositions of the invention, it is possible to manufacture caps with a maximum length of about 4 inches which have delay intervals up to 15 seconds or greater. For example, the components of the cap illustrated in Figure 1, other than the delay element, consume about 1½ inches of the total cap shell length. Therefore, there is available within a cap shell 4 inches in length, a space of about 2½ inches to house the delay element. Referring to Figure 2, it can be seen that a delay interval of about 16 seconds can be obtained by using about 2.4 inch lengths of delay element containing compositions 1 or 2 in such a cap. The selection of even slower burning compositions of the invention would result in 4 inch caps with delay intervals even greater than 16 seconds.

Example 2

The following table illustrates two further compositions of the invention in which selenium and tellurium are interchanged. These compositions were prepared and used in caps as heretofore described. The delay elements were 0.75 inch in length.

TABLE

Composition	Ingredients, percent by weight					Mean Delay Interval, Secs.
	Pb ₃ O ₄	PbCrO ₄	Se	Te	Si	
3	45.8	43.6	2	—	8.6	1.78
4	45.8	43.6	—	2	8.6	1.43

It is to be understood that the foregoing examples and details are for the purpose of illustration only and that the invention is not limited thereto but may be modified and embodied in various other forms without departing from its intended scope. A particular modification which is desirable when using the slower burning

60

composition of the invention in the delay elements of ventless delay electric blasting caps is the use of a delay element priming charge comprising a faster burning composition of the invention, said delay element priming charge being pressed on top of the delay element.

It will be further understood that the invention is not limited to the preferred compositions described herein, nor to the particular cap structure illustrated. In the foregoing description of the invention, only its application in ventless delay electric blasting caps has been shown. It is apparent, however, that the invention has many other important applications such as for example in delay fuses required in various types of military explosive devices and in the delay elements for detonating fuse delay connectors.

What we claim is:

1. A substantially gasless, slow-burning delay composition consisting essentially, per 100 parts by weight of said composition, of 6.5 to 50 parts of fuel and 93.5 to 50 parts of oxidising material, said fuel consisting essentially of a mixture of not less than 60% by weight of silicon and not more than 40% by weight of solid, non-metallic material selected from the group consisting of selenium and tellurium, and said oxidising material comprising a mixture of lead oxides and water-insoluble metallic chromates containing not less than 30% by weight of lead oxides.
2. A substantially gasless, slow-burning delay composition consisting essentially, per 100 parts by weight of said composition, of 7 to 65 parts of fuel and 93 to 35 parts of oxidising material, said fuel consisting essentially of a mixture of not less than 17% by weight of silicon and not more than 83% by weight of solid, non-metallic material selected from the group consisting of selenium and tellurium, and said oxidising material being selected from the group consisting of lead peroxide and red lead.
3. A substantially gasless, slow-burning delay composition consisting essentially, per 100 parts by weight of said composition, of 10 to 40 parts of fuel and 90 to 60 parts of oxidising material, said fuel consisting essentially of a mixture of not less than 80% by weight of silicon and not more than 20% by weight of solid, non-metallic material selected from the group consisting of selenium and tellurium, and said oxidising material being selected from the group consisting of barium chromate and lead chromate.
4. A substantially gasless, slow-burning delay composition consisting essentially, per 100 parts by weight of said composition, of 1.6 to 1.7 parts of selenium, 6.1 to 6.2 parts of silicon, 36.0 parts of red lead, 35.9 parts of lead chromate and 20.3 parts of barium chromate.
